UNITED STATES PATENT OFFICE

FRANK A. BROWNE, OF WAYNE, PENNSYLVANIA, ASSIGNOR TO THE BARBER ASPHALT COMPANY, OF PHILADELPHIA, PENNSYLVANIA, A CORPORATION OF WEST VIRGINIA

AUTOMATIC VALVE

Application filed August 20, 1926. Serial No. 130,424.

The invention relates to a valve especially adapted for use as the automatic control valve in a circulatory refrigerating system of the flooded type; that is to say, a system in which 5 a definite quantity of refrigerant is compressed, condensed into liquid form, and after passing through the automatic valve is evaporated for purposes of refrigeration, and returned to the compressor. Such a valve automatically 10 functions to control the flow of liquid refrigerant from the high pressure side to the low pressure side.

The refrigerant passes through the automatic valve in liquid form and it is desirable 15 that there be means whereby said valve is automatically controlled, so that the quantity of liquid on the low pressure side is fairly constant. This has heretofore been accomplished by a float valve wherein the opening 20 or shutting of the valve is controlled by the level of liquid on one side or the other. According to my invention the opening or shutting of the valve is dependent upon the weight of liquid refrigerant in the boiler. 25 When a certain weight of liquid is attained in the boiler a counterweight is over-balanced and the valve closed. When evaporation has sufficiently reduced the weight of liquid in the boiler the valve opens.

Instead of utilizing the total weight of 30 liquid in the boiler to actuate the valve controlling the flow of liquid into the chamber, the weight of a surplus of liquid above a predetermined amount is utilized to actuate 35 the valve. The operation is thus dependent on the total amount of liquid in the boiler though only a portion of the liquid actually operates the valve.

By my construction, I provide a compact 40 and efficient automatic control for the valve, positive in its action and free from any impediment tending to produce inoperativeness, or requiring attention to keep the valve in order. Other objects and advantages will be 45 apparent from the following description of a typical embodiment of my invention, while the subjoined claims serve to define those features which are deemed novel in the art.

50 In the drawings:

Fig. I is a longitudinal section of my improved automatic valve.

Fig. II is a section taken substantially as indicated by the arrowed lines II—II in the preceding illustration; and,

Fig. III is a similar section on the plane designated III—III in Fig. I.

Referring more in detail to the several views my automatic valve is enclosed in a "boiler" or evaporator casing 5, conveniently 60 of cylindrical form, with one end 6 permanently closed in, while the other is fitted with a removable head 7 secured thereto in any of the well known ways. The removable head 7—as well as the cylindrical shell flange 8—is of comparatively heavy section, whereas 65 the other portions are relatively thin. This head 7 is provided with an open-top dished compartment 9 having a lateral lip or weir 10. The liquid refrigerant is conducted from any suitable source by way of a conduit 11 into the tube 12 supported by the removable head 7.

The tube 12 forms what is termed the freezing chamber. The conduit 11 enters the same 75 at its upper portion so that any water contained in the refrigerant gravitates to the bottom of said freezing chamber, and is therein frozen or separated from the refrigerating medium. Secured on the inner end of the 80 tube or freezing chamber 12 is a fitting 13 having a passageway 14, controlled by a non-return valve indicated at 15. This is the automatic control valve of the refrigerating system and by it the refrigerating medium 85 is admitted from said freezing chamber 12 into the boiler 5, which constitutes part of the low pressure or refrigerating element of the system, wherein the liquid boils off into vapor. The valve opening which is controlled 90 by the automatic valve is below the normal level of the liquid refrigerant in the boiler 5. This prevents the liquid refrigerant from flashing into vapor at the valve seat.

The proper control of the valve 15 is accomplished by a pendulum member 16 pivoted at 17 between angled forks 18 integral with the fitting 13 aforesaid. Supported by the pendulum member 16 is a longitudinally directed rod 19 which has rigidly secured to 100

its outer end 20, an open-top pan 21 made of thin sheet material and adapted to rise and fall within the dished compartment 9. Adjustably secured on the inner end of the rod 19 is a counterweight 22 which is functional to over-balance the pan 21 when there is little or no liquid therein, as later on explained. 23 indicates the return connection from the boiler 5 to the compressor.

The operation of my novel automatic valve is briefly as follows:—Assuming that the boiler 5 is gradually filling with liquid, it will be obvious that when it rises to the level of the weir 10 it will flow thereover into the open-top pan 21 and partly fill the same; or, to a sufficient extent—such as indicated in Fig. 1—so that the added weight will overbalance the counterweight 22 and rock the member 16 inwardly thereby effecting closure of the valve 15. Incidentally the pan 21 is prevented from rising too high by contacting with the weir 10 as will be understood from Fig. 1. Closing of the valve 15 automatically discontinues flow of refrigerant into the boiler 5; and, by evaporation, the liquid in the pan 21, will be gradually removed until the counterweight 22 overbalances said pan and re-opens the valve 15. In the meantime the level of the liquid in the boiler 5 will, similarly, have been lowered by evaporation of said liquid. Upon reopening of the valve 15 the liquid level again rises in the boiler 5 until it reaches the weir 10, whereupon the cycle of operations above set forth will be automatically repeated.

The open-top pan 21 operates in the dished compartment 9 free of all external liquid influence tending to buoyantly support or float the same. In other words, the pan 21 is only affected by liquid flowing thereinto and never by exterior liquid that would cause it to "float".

The pan 21 is of a cubic content sufficient to effectively preclude its ever being filled to an "overflow" level. Any condensation finding its way into—or settling in—the dished compartment 9 is the more promptly dissipated because the compartment connects with the head 7 which is an active conductor of heat.

While I have shown a particular construction of my novel automatic control valve, it is to be understood the details as to form and arrangement of the parts thereof are susceptible of variation within the scope of the claims.

Having thus described my invention, I claim:

1. A fluid chamber with a valved entrance, a compartment in the chamber having a weir, and a control for the valved entrance which includes a receptacle situated in the compartment aforesaid and adapted to receive overflow over the weir to effect closure of the

entrance and on evaporation of said overflow to reopen said entrance.

2. An automatic fluid boiler embodying a valved entrance, a dished compartment in the boiler having a weir, and a control for the entrance comprising a member actuated by an open-top pan in the dished compartment receiving overflow of fluid over the weir and by evaporation of said overflow.

3. An automatic fluid boiler embodying an entrance for the boiler, a dished compartment in the boiler having a weir, a control for the aforesaid entrance embodying a counterbalanced member functional to open the entrance aforesaid, and co-ordinated means in the dished compartment influenced by overflow over the weir to close said entrance.

4. An automatic refrigerant boiler embodying a substantially closed-in chamber with an outlet at its upper level into the boiler, a dished compartment in the boiler having a weir, a discharge control for the aforesaid outlet embodying a counterbalanced pivoted member functional to open the outlet aforesaid, and a co-ordinated pan in the dished compartment adapted to receive overflow over the weir to close said outlet.

5. In a refrigerating system an automatic valve admitting liquid refrigerant to a refrigerating compartment on the low pressure side and in which said liquid is evaporated; another evaporating compartment subject to the same low pressure into which the liquid overflows upon reaching a predetermined level in the first mentioned refrigerating compartment; a pan in the latter compartment receiving said overflow and actuating means for the automatic valve whereby said overflow closes it and whereby evaporation of the overflow reopens it.

6. In combination, a chamber having an entrance through which volatile liquid may flow into the chamber, a valve controlling flow through the entrance, and a receptacle arranged to receive liquid from the chamber when the level of the liquid in the chamber reaches a predetermined height and movable by the weight of such received liquid to close the valve.

7. In combination, a chamber having an entrance through which volatile liquid may flow into the chamber; a valve controlling flow through the entrance, and a receptacle arranged to receive liquid from the chamber when the level of the liquid in the chamber reaches a predetermined height and movable by the weight of such received liquid to close the valve, said receptacle moving oppositely upon evaporation of received liquid to close the valve.

8. In combination, a chamber having an entrance through which volatile liquid may flow into the chamber, a valve controlling flow through the entrance, a receptacle arranged to receive liquid from the chamber

when the level of the liquid in the chamber reaches a predetermined height and movable by the weight of such received liquid to close the valve, and adjustable means resisting movement of the receptacle under the weight of received liquid.

In testimony whereof, I have hereunto signed my name at Philadelphia, Pennsylvania, this 5th day of August, 1926.

FRANK A. BROWNE.
